UNITED STATES PATENT OFFICE

GIUSEPPE BENEDETTO, OF NOVARA, ITALY, ASSIGNOR TO THE OMES HOLDING COMPANY LIMITED, OF LONDON, ENGLAND, A BRITISH COMPANY

PROCESS FOR EFFECTING THE PRESSING OF METALS AND APPARATUS THEREFOR

Application filed September 11, 1930, Serial No. 481,334, and in Italy September 14, 1929.

The present invention relates to electric machines for effecting the forging of metals by upsetting enlarged portions thereon. It is old to provide a machine comprising an anvil against which a bar or ingot to be upset is pushed while a strong electric current is passed through the bar to heat it.

In apparatus of this kind a common difficulty lies in the fact that the electrical resistance of the work decreases with the increase of cross section brought about during the upsetting operation. Ordinarily the electric current is conducted into the work through the jaws of a vice in which the work is held and between which and the anvil the upsetting operation proceeds. Close to the vice the cross section of the work is not increased by the upsetting and therefore at this point the current density becomes much higher than in the body of the work and a common trouble in such machines is "burning" of the metal due to over-heating by the excessive current density at the neck by the vice. This trouble is particularly met with in machines where the work slides through the vice jaws during the upsetting operation so that heads of large diameter can be upset. It is an object of the invention to provide means for overcoming the said difficulty.

According to the present invention there is provided an electric upsetting apparatus comprising in combination an anvil, a vice in front of the anvil, means for causing an electric current to pass through work held between the vice and the anvil, means for forcing the work and the anvil towards one another for forming an upset head and means for so regulating the electric current as to prevent substantial increase thereof when the head is formed.

Alternating current supply apparatus designed to give a constant current has been well known for many years and obviously it would be within the scope of the present invention to employ any such apparatus which might be found suitable for the purposes of the invention. Preferably, however, according to the present invention the means for preventing substantial increase of electric current comprises a transformer having one

of its windings (for example the secondary winding) movable relatively to the other and means for yieldingly urging the said movable winding towards the other winding of the transformer.

With the arrangement furnishing current at a fixed intensity, and always not greater than that which the section of the bar will sustain, the heating is conducted with all security and without fear of failure. Further, as the stated cause of damage is no longer to be feared one may, from the commencement of the operation, apply the necessary tension for the normal intensity of the current, shortening the duration of the operation as compared with the result. High economies of current and of labour are thus attained.

The accompanying drawings illustrate the essential parts of an apparatus in accordance with the present invention by way of example and in the drawings:—

Figure 1 is a front elevation,

Figure 2 is a plan,

Figure 3 is a diagrammatic representation of a transformer provided with a movable bobbin and its electric connections to the apparatus shown in Figures 1 and 2, and

Figure 4 is a side elevation partly in section of one construction of transformer with a movable bobbin.

Referring to Figures 1 and 2 the machine comprises a frame 11 having guideways 12 along its upper surface upon which are mounted an anvil slide 13 at one end, a vice slide 14 adjacent to it, a guide vice 15 and at the other end a hydraulic ram cylinder 16. All these parts except the anvil carrier 13 are movable longitudinally along the guideways.

In the body of the anvil carrier is a vertical bearing to receive a vertical stem which carries a headstock casting 20 having a horizontal bearing having a mandrel 21. The mandrel 21 carries a worm-wheel 22 at one end which is engaged by a worm 23 operated by a hand wheel 24 mounted in bearings 25 on the headstock 20. Thus the mandrel 21 may be rotated as desired and the axis of the mandrel may be set at any angle to the guideways 12.

by rotating the headstock 20 upon its vertical stem mounting in the carrier 13.

Suitable means for locking the stem of the headstock 20 when set in any desired position are provided and comprise a clamping bolt 26 working in a slot 27 in the frame 11.

Within the mandrel 21 which is hollow there is mounted the stem of an anvil 28 having a working face 29 which is directed towards the right in Figure 1. The anvil 28 is made hollow and provided with water circulating connections to keep it cool, which connections are not shown in the drawings as they are of usual construction. They comprise flexible tubes for the conveyance of the cooling water to and from the movable anvil. The working face of the anvil is made removable from the main portion and is composed of a high conductivity copper-tungsten alloy of a hard and durable kind.

The anvil carrier 13 is insulated from the guideways 12 by interposed insulating material, which however, as it does not have to withstand a high electric potential may be of no great thickness provided it is capable of withstanding the heavy clamping forces necessary to secure the parts together.

The vice carrier 14 is movable along the guideways 12 under the control of a lead screw 17 which is engaged by a wormwheel 18. The wormwheel 18 is rotatable by a worm on the shaft of a handwheel 19 so that the vice carrier 14 may readily be set by the operator at any desired position on the bed 33 of the machine relatively to the anvil.

The vice carrier comprises a fixed lower jaw 30 and a movable upper jaw 31 mounted on a stem 32 projecting from a hydraulic pressure cylinder 33. A return spring 34 is provided to draw the upper vice jaw 31 normally upwards. A pressure supply pipe 35 to the cylinder 33 is provided which is under the control of a two-way valve 36 operated by a control handle 37. By this means hydraulic pressure can be applied from a supply pipe 38 to the cylinder 33, or alternatively the cylinder may be connected through the two-way valve to an exhaust pipe 39. The vice and the carrier therefor are constructed of bronze or other high conductivity material and the same applies to the anvil headstock. These two parts are connected to the secondary terminals 40, 41 of a step-down transformer 42 which is not shown in Figures 1 or 2 but appears in the connection diagram of Figure 3. The transformer may conveniently be located in the base of the machine. A main control switch 44 is provided for the transformer and this is linked by suitable operative connections to a switch control handle 45.

The hydraulic ram cylinder 16 is movable along the guideways 12 by a lead screw 46 and the longitudinal movement is controlled by a handwheel 47 similarly to the handwheel 19 which controls the longitudinal movement

of the vice carrier 14. The cylinder 16 operates a ram 48 which engages a cross head 49, mounted to slide along the guideways 12. The cross head 49 carries an interchangeable ram 50 which is intended to abut upon the end of a workpiece held in the vice jaws 30, 31 so that the other end thereof abuts upon the working face 29 of the anvil. The cross head 49 carries slide bars 51 which are attached to cables 52 passing over pulleys 53 and which at their other ends are secured to a counterweight 54.

The counterweight 54 not only serves to draw the ram 50 backward when hydraulic pressure is cut off from the cylinder 16 but also serves a second useful purpose in that it ensures that there is no backlash in the operative connections between the handwheel 47 and the cylinder 16.

Upon the upper side of the cylinder 16 is a valve box 55 which carries a valve details of which are not shown in the drawings and which may be of any desired type for opening communication between the two sides of a piston working in the hydraulic cylinder 16. When such communication is opened the force on the ram 50 is reduced or equalized and advanced movement caused to cease. To operate the valves in the valve box 55 there is provided an adjustable screw 56 which is screw-threaded in a movable valve operating portion of the valve box and which passes freely through the cross head 49 to an operating handle 57. A locking handle 58 is provided which serves to hold the screw 56 in any position to which it has been adjusted. The effect of this arrangement is that when the cross head 49 reaches the handle 57 in the course of its forward movement it operates the valve in the valve box 55 and further advance movement of the ram 50 is prevented. Thus the ram can be set to execute a predetermined stroke.

Hydraulic pressure is supplied to the cylinder 16 through a supply pipe 59 having a telescopic section 60 attached to a two-way valve 61. The two-way valve 61 is controlled by a handle 62 and receives hydraulic pressure from the pipe 38 while it is provided with an exhaust connection 63.

Between the vice carrier 14 and the ram 50 there is located a guide vice 15. The guide vice 15 is not operated and comprises a pair of horizontally movable jaws 64, 65 actuated by a right and left hand screw on the spindle 66 of a hand lever 67. The guide vice may be removed from the machine if short pieces of work are under treatment but for long pieces of work it grips the work close to the ram 50 and holds it central with the end of the ram.

Turning to Figure 3 this comprises a low tension step down transformer 42 as already referred to the secondary of which is connected by the terminals 40, 41 to the vice and

the anvil respectively so that electric current can be supplied to heat the work between the vice and the anvil. The primary of the transformer 42 is provided with a number of tappings operated by a hand switch 68 and is connected to a movable secondary winding 69 of a control transformer 70. The primary winding 71 of the control transformer is connected to the source of electric supply.

10 The secondary winding 69 is mounted so as to slide freely on a vertical magnetic core 72 and its weight is partly counterbalanced by a counterweight 73 connected to the winding through a balance beam 74.

15 The construction of the movable bobbin transformer is indicated only diagrammatically in Figure 3 but is shown in more detail in Figure 4.

In Figure 4 the parts are mounted in an oil containing casing 75 and the position of the primary windings 71 and secondary windings 69 can be clearly seen, the latter being slidably mounted on a vertical magnetic core 72 as already described. The balance beam 74 is for the sake of compactness divided into two portions 74, 76 which are interconnected by spur-wheels 77, 78. The balance weight 73 is slidably mounted upon the upper section 76 of the balance beam and is connected to an operating chain 79. The operating chain extends around a chain wheel 80 at one end of the beam and a chain wheel 81 at the other. The chain wheel 81 rotates about a vertical axis which intersects

35 the axis of rotation of the spur-wheel 78 about which the section 76 swings. A vertical shaft 82 carries at its lower end cross pins 83 and the end of the shaft 82 carrying the cross pins is entered within a hollow boss 84

40 which forms part of the chain wheel 81. The disposition of the parts is such that the cross pins 83 engage the boss 84 loosely at or about the point of intersection of the axis of the chain wheel 81 and the balance beam

45 76. Consequently the vertical shaft 82 can rotate the chain wheel notwithstanding oscillation of the balance beam 76 about its axis. The shaft 82 is telescopically connected to a second shaft section 85 operated

50 through a Hook's joint 86 by a handwheel 87 outside the casing. By the described connections a counterweight 73 may be pulled by the chain 79 into any desired position of adjustment along the balance beam 76.

55 The weight 73 is not adequate to overcome the weight of the secondary winding 69 but only partially to balance it and thus the natural repulsion between the primary 71

60 and the secondary 69 becomes, at a certain predetermined current, dependent upon the position of the balance weight 73, adequate to overcome the unbalanced weight of the secondary 69 and to force the latter upwards,

65 thus increasing the leakage between the pri-

mary and secondary and reducing the secondary voltage.

In the operation of the machine a work-piece is placed between the ram 50 and the anvil 29 being gripped by the vice jaws 30, 31 and if necessary additionally supported by the vice jaws 64, 65. In order to bring the ram 50 into contact with the work the cylinder 16 may be initially adjusted along the guideways by the handwheel 47. The vice carrier 14 is set at such a distance from the anvil face 29 as to allow room for the head which it is desired to form upon the work. Current is then switched on by the handle 45 and hydraulic pressure is applied to the cylinder 16 by operating the handle 62. As soon as the work becomes sufficiently heated by the electric current the ram 50 forces the work through the vice jaws with a sliding action and upsets a head between the anvil 29 and the vice jaws.

The operation of the transformer 70 prevents overheating of the work at the neck between the vice jaws and the upset head, which would otherwise occur owing to the reduction of resistance which takes place when the section of the metal is increased by the upsetting operation. The current can further be hand-controlled by the handle 68 if desired but generally speaking this handle 25 needs only to be set at a different position for different sizes of work, a corresponding alteration in the counterweight 73 being effected if desired.

By rotating the working face of the anvil 29 about a vertical axis it can be set to various degrees of inclination to the line of advance of the workpiece and located in this position by the bolt 26. This permits of the formation of lopsided or angularly inclined heads. Moreover the anvil face may be rotated in its own plane by operating the handwheel 24 during or after the upsetting operation. This permits of the production of various twisted shapes. The working face of the anvil may be recessed moreover to further shape the head of the work.

I claim:—

1. An electric upsetting apparatus comprising in combination an anvil, a work-holding vice in front of the anvil, means for forcing work held in the vice so as to extend toward the anvil and the anvil towards one another for forming an upset head, a constant current transformer having one of its windings movable relatively to the other under the influence of means for yieldingly urging the said movable winding towards the other winding of the transformer, and means whereby the secondary circuit of the 115 said transformer may supply electrical energy for heating the work held between the vice and the anvil.

2. An electric upsetting apparatus comprising in combination, an anvil, a vice in 120

front of the anvil having jaws to hold the work and convey electric current thereto while permitting sliding movement of the work through the vice jaws towards the anvil, a ram to engage the end of the work remote from the anvil and force the work through the vice jaws, means for supplying pressure to the ram, a constant current transformer having one of its windings movable 10 relatively to the other under the influence of means for yieldingly urging the said movable winding towards the other winding of the transformer, and electric connections whereby the output energy of the said transformer is applied to heat the work between the vice and the anvil.

3. An electric upsetting apparatus as claimed in claim 1 wherein the movable bobbin of the transformer is slidably mounted 20 upon a vertically extending core and an adjustable counterweight is provided operatively connected to the bobbin for the purpose described.

4. Electric upsetting apparatus as claimed 25 in claim 1 wherein the secondary of the movable winding transformer is electrically connected to a step down transformer the secondary of which is electrically connected to the vice jaws and the anvil respectively.

30 In testimony whereof I affix my signature.

GIUSEPPE BENEDETTO.
